(57) CLAIM

The ornamental design for a fasten tongue jack pad, as shown and described.

DESCRIPTION

FIG. 1 is a top, front, right side perspective view of a fasten tongue jack pad showing our new design;
FIG. 2 is a bottom, back, left side perspective view thereof;
FIG. 3 is a top plan view thereof;
FIG. 4 is a bottom plan view thereof;
FIG. 5 is a front elevational view thereof, the back elevational view being a mirror image thereof; and,
FIG. 6 is a left side elevational view thereof, the right side elevational view being a mirror image thereof.
The broken lines illustrate portions of the fasten tongue jack pad that form no part of the claim.
